FIG. 1

FIG. 2

FIG. 3

FIG. 4

FIG. 5 FIG. 6

FIG. 7 FIG. 8

Fig. 1 is a view in perspective of a latching unit for doors showing my new design, and showing the hook and eye portions of the fastener in latched relationship;

Fig. 2 is a front elevational view thereof showing the parts in unlatched relationship;

Fig. 3 is a rear elevational view of Fig. 2;

Fig. 4 is a top plan view of Fig. 2;

Fig. 5 is a right end elevational view of the eye portion of the unit;

Fig. 6 is a left end elevational view of the eye portion;

Fig. 7 is a left end elevational view of the hook portion of the unit; and

Fig. 8 is a right end elevational view of the hook portion.

The essential features of the design reside in the solid line portions.

I claim:

The ornamental design for a latching unit for doors, as shown and described.
